SHARPENING INSTRUMENT

Bernard Mark Miller, Sheffield, England

Application January 21, 1944, Serial No. 519,126
In Great Britain December 9, 1943

2 Claims. (Cl. 51—205)

This invention relates to sharpening devices. Hitherto it has been customary to sharpen knives such as carving knives on a sharpening device known as a "steel." This consists of a body member of rod-like shape made of steel 5 provided with a tang fitting into a handle.

This device is, however, unsuitable for the sharpening of hollow ground carving knives as such carving knives have cutting edges of wafer thickness which are liable to injury when brought into contact with hard steel, and it is an object of the present invention to provide an improved device suitable for sharpening hollow ground carving knives.

With this object in view the present invention provides a sharpening device comprising a body member, preferably of rod-like form, having at least one groove therein filled with a mass containing abrasive material bonded to the surface of the groove, the surface of the said mass being level with or projecting beyond the surface of the body member which is made of material softer than that of the abrasive so that it will wear away as the abrasive wears away.

Preferably a plurality of grooves are provided filled with abrasives of different fineness so that the device may be used both as a hone and a strop.

Examples of materials which may be used as abrasives are silicon carbide and diamond dust.

Examples of materials which may be used for the body member are brass, bronze and copper.

It will be understood that the body member may be provided with a tang fitting into a handle of the kind usually employed in the sharpening devices known as steels.

The invention will now be described in greater detail by way of example with reference to the accompanying drawing, in which:

Fig. 1 is an elevation of a sharpening device according to the invention.

Fig. 2 is a section on the line A—A of Fig. 1, and

Fig. 3 is a similar sectional view of the body member before the filling of the grooves with the abrasive.

Referring to the drawing, the sharpening device consists of a body member 1 of brass or other suitable soft material having four grooves, 2, 3, 4 and 5, filled respectively with masses containing silicon carbide or other suitable abrasive 6, 7, 8 and 9, the grains of abrasive in the masses 6 and 8 being substantially coarser than those in masses 7 and 9. The body member 1 is provided with a tang 10 fitting into a handle 11.

I claim:

1. A device for sharpening carving knives comprising a brass body of rod-like form having four longitudinal grooves therein, a mass containing silicon carbide or other suitable abrasive bonded to the surface of each of said grooves, the granular size of the abrasive in two of said grooves diametrically opposed to each other being greater than the granular size of the abrasive in the other two grooves and the surfaces of the masses projecting beyond the surface of the body member.

2. A device for sharpening carving knives comprising a soft metal body of rod-like form having four longitudinal grooves therein, a mass containing a suitable abrasive bonded to the surface of each of said grooves, the granular size of the abrasive in two of said grooves diametrically opposed to each other being greater than the granular size of the abrasive in the two other grooves and the surfaces of the masses projecting beyond the surface of the body member.

BERNARD MARK MILLER.
